UNITED STATES PATENT OFFICE.

JAMES H. CRAWFORD, OF DEADWOOD, SOUTH DAKOTA.

COMBINED KNIFE AND FORK.

1,425,750.

Specification of Letters Patent. Patented Aug. 15, 1922.

Application filed December 20, 1920. Serial No. 481,991.

To all whom it may concern:

Be it known that I, JAMES H. CRAWFORD, a citizen of the United States, residing at Deadwood, in the county of Lawrence and 5 State of South Dakota, have invented certain new and useful Improvements in Combined Knives and Forks, of which the following is a specification.

This invention relates to cutlery and more 10 particularly to a combined knife and fork especially designed for use by soldiers, campers, travelers and others in lieu of the ordinary knife and fork.

The object of the invention is to provide a 15 comparatively simple and thoroughly sanitary device of this character, the parts of which may be compactly assembled so as to permit the device to be conveniently carried in the pocket without liability of exposing 20 the cutting edge of the knife or offering any surface obstruction which would tend to catch in the pocket and tear or otherwise injure the clothing.

The invention further aims to provide a 25 combined knife and fork including coacting members each provided with a handle having a terminal retaining flange or lip spaced laterally therefrom to form a pocket for the reception of the active end of the adjacent 30 member, said members being separable laterally so as to permit of their individual use when desired.

The invention further contemplates forming both the knife and fork in such a manner 35 that each may be stamped from a single sheet of metal and to so shape the parts that they will present a symmetrical appearance when either assembled or separated.

A further object is to provide a flat metal 40 fork the tines of which are bowed laterally to increase the serviceability of the fork and also to cause the tines to frictionally engage the retaining lip of the knife and thus prevent accidental separation of the parts when 45 assembled.

A still further object of the invention is generally to improve this class of devices so as to increase their utility, durability and efficiency.

50 In the accompanying drawings:

Figure 1 is a perspective view of a combined knife and fork embodying the present invention showing the elements in assembled position;

55 Fig. 2 is a longitudinal sectional view

taken on the line 2—2 of Fig. 1 and looking in the direction of the arrows;

Fig. 3 is a perspective view of the knife and fork detached or separated.

Corresponding and like parts are referred to in the following description and indicated in all the views of the drawings by the same reference characters.

The device comprises two articles of utility, one of which is preferably in the form of 65 a knife 5 and the other in the form of a fork indicated at 6. Each article is preferably stamped or otherwise formed from a single sheet of flat metal, the fork 6 being provided at one end thereof with a handle 7 and at 70 its opposite ends with spaced tines 8. The knife 5 is also provided at one end thereof with a handle 9 similar in construction to the handle 6, and at its opposite end one longitudinal edge of the knife is inclined 75 or beveled to form a cutting edge 10 which preferably extends around the point of the knife as best shown in Fig. 3 of the drawings. The metal at the end of the handle 80 of each member is bent or folded upon itself to form an overhanging retaining lip 11, which is spaced laterally from the side face of the handle to form a pocket 12 for the reception of the active end of the adjacent member when said members are 85 assembled. The opposite longitudinal edges of the members 5 and 6 are preferably curved inwardly as indicated at 13 to form a reduced neck so as to permit said members to be conveniently grasped in the hand 90 when using the same. The tines 8 are preferably bowed or bent laterally as indicated at 14 so as to increase the holding capacity of the fork and consequently its serviceability.

The lips 11 are preferably resilient so 95 that when the members 5 and 6 are assembled in the manner shown in Fig. 1 of the drawings said lips will frictionally engage the active ends of the members and hold them from accidental separation. It 100 will here be noted that by having the tines bowed outwardly as indicated at 14 not only will the holding capacity of the fork be increased but said tines will frictionally engage the adjacent retaining lip 11 and further assist in preventing accidental separation of the members.

It will thus be seen that by grasping the device at the contracted portion 13 thereof and exerting a slight lateral pressure on the 110

members 5 and 6 said members may be separated and in which position they may be used in the ordinary manner. In order to assemble said members it is merely necessary to insert the active end of the knife 5 beneath the spring lip 11 of the fork 6 and the tines 8 beneath the spring lip of the knife 9 and press laterally on said members, thereby causing the same to assume the position shown in Fig. 1 of the drawings, and in which position they may be conveniently carried in the pocket. The knife blade 5 is preferably of slightly less width than the handle 7 of the fork so that when the members 5 and 6 are assembled the handle 7 of the fork will form a guard or protection for the cutting edge 10 of the knife and permit the device to be conveniently handled without cutting or otherwise lacerating the hand of the user. It will furthermore be noted that inasmuch as the members are free from surface projections liability of the parts catching in the pocket and tearing or otherwise injuring the clothing is reduced to a minimum. While I have shown two articles of utility embodied in the present invention one of which is a knife and the other a fork, it will, of course be understood that a spoon or other desired implement may be substituted for either the knife or fork if found desirable without departing from the spirit of the invention.

It will furthermore be understood that the devices may be made in different sizes and shapes and nickelized japanned or otherwise coated so as to give them a neat attractive appearance.

Having thus described the invention, what is claimed as new is:

40 1. A device of the class described including articles of utility of equal length each having one end thereof provided with means adapted to engage the opposite end of an adjacent article for holding the articles in assembled position.

45 2. A device of the class described including coacting articles of utility each provided with a handle having a terminal overhanging lip extending entirely across the same and spaced laterally therefrom to form a pocket for the reception of the opposite end of a mating article.

50 3. A device of the class described including coacting articles of utility each having a flat handle terminating in an overhanging resilient retaining lip of the same width as the handle and adapted to frictionally engage the adjacent end of the mating article for holding said articles in assembled position, said articles being separable laterally to permit the individual use thereof.

55 4. A device of the class described including coacting articles of utility each having its intermediate portion reduced and one end thereof flat to form a handle terminat-

ing in an overhanging resilient retaining lip of the same width as the handle and adapted to frictionally engage the opposite end of an adjacent article for holding the articles in assembled position.

70 5. A device of the class described including coacting articles of utility, one of which is provided with a knife edge and the other with tines constituting a fork, each article being formed with a handle having an overhanging retaining lip of the same width as the handle and adapted to engage the active end of the mating article for holding said articles in assembled position, said articles being separable laterally to permit the individual use thereof.

75 6. A device of the class described including coacting articles of utility of equal length, one of said articles being provided with laterally bowed tines constituting a fork and having a flat handle, the end of which is bent upon itself to form an overhanging retaining lip coextensive with the width of the handle, the other article being provided with a knife edge and a handle the end of which is bent to form an overhanging retaining lip of the same width as the first-mentioned lip, the lip on the handle of the knife being adapted to bear against the outer faces of the tines of the fork and the lip on the handle of the fork being adapted to frictionally engage the active end of the knife when said articles are assembled.

80 7. A device of the class described including coacting articles of utility each including a service portion and a handle portion, the handle portion of each article being bent upon itself to form an overhanging retaining lip coextensive with the width thereof and adapted to frictionally engage the service portion of the adjacent article when the articles are assembled, said articles being separable laterally to permit individual use thereof.

85 8. A device of the class described including articles of utility of the same length adapted to lie flat one upon the other when in assembled position and each including a handle portion and a service portion, the handle portion of one of the articles being bent in one direction to form an overhanging retaining lip and the handle portion of the other article being bent in the opposite direction to form a similar retaining lip, each lip being coextensive in width with the adjacent handle portion, the lip on the handle of one article being adapted to frictionally engage the service end of an adjacent article when said articles are assembled and said articles being separable laterally to permit individual use thereof.

90 9. A device of the class described including coacting articles of utility, one of which is provided at one end thereof with a handle and at its opposite end with spaced tines

constituting a fork, the other article being provided at one end thereof with a handle and having its other end of less width than the handle of the fork and beveled to form a cutting edge, the free end of the handle of each member being bent to form an overhanging retaining lip extending entirely

across said handle, one of said lips being adapted to engage the tines and the other the reduced portion at the knife edge, the handle of the fork forming a guard for the knife edge when the articles are assembled.

In testimony whereof I affix my signature.
JAMES H. CRAWFORD. [L.S.]
